United States Patent Office.

D. FRANK DODGE, OF LOWVILLE, NEW YORK.

Letters Patent No. 79,214, dated June 23, 1868.

IMPROVED MAIL-BAG.

The Schedule referred to in these Letters Patent and making part of the same.

Be it known that I, D. FRANK DODGE, of Lowville, in the county of Lewis, and State of New York, have invented a new and useful Bag or Pouch for the Transfer and Handling of Mail-Matter; and I do hereby declare that the following is a full, clear, and exact description of the construction and operation of the same, reference being had to the accompanying drawings, making part of this specification, in which—

Figure 1 is a perspective view of the bag as seen closed.

Figure 2 represents the frame and mouth of the bag open.

Figure 3 is a sectional view crosswise of the frame, and

Figure 4 is a view of the lock-bolt, with the shield removed—

Like letters designating like parts:

A B are a pair of heavy sheet-metal or malleable-iron jaws, the ends of which are turned at right angles to the longitudinal section of each plate, and are formed in such a manner, as shown fully in fig. 3, that by uniting the two separate parts by the rivets C C, the two may be partially rotated upon the said rivets as upon a hinge.

Upon the upper or outer edge of the jaw A there is a narrow flange, turned inward the whole length of the plate at right angles to the vertical plane of the plate. This flange serves the double purpose of stiffening the jaw, and when the jaws are closed, the flange shuts over the edge of the jaw B, making a close joint, and precluding the introduction of any instrument to pry the jaws apart.

D is a strong bolt, secured to the inside of B, one end of which is formed into the loop d, and works through an opening in the flange, b, upon one end of the jaw B. Upon the body of the bolt proper are a couple of tongues, e e, the form of which is shown fully in fig. 4. This bolt has a stud upon its opposite side, which projects through a longitudinal opening in the plate B, and has a button, G, upon the outside, by which the bar can be moved endwise. This bolt is enclosed and firmly secured in its place by the semicircular shield E, one end of which is secured by a stud upon the plate b, while the opposite end is fastened by the screw S, which passes through the loop d on the bolt D. g g are a couple of vertical slots or openings on the circumference of the shield E, and are opposite the tongues e e upon the bar D. On the inside of the plate A, and directly opposite these openings g g, are firmly secured the projections f f, through which are apertures fitting the tongues e e, and through which the same pass when the jaws are brought together, and the bar moved endwise by means of the button G. There is also an opening in the end flange, d, of A, corresponding with a similar opening in b, through which the loop d projects.

The body of the bag I construct in a manner different from the mail-bag in general use, being of two side pieces, J J, with a third piece or bolster-strip, H, firmly riveted or stitched around the two sides and one end of the pieces J J, and the three securely attached to the mouth-frame or jaws by the rivets i i. K L are loops, of leather or cloth, by which the bag is handled in actual service.

Having thus described the construction of my improved bag, before passing to describe its use, I wish to refer to the construction of those now universally used by the mail department of our Government, that my improvements may be the better understood. The ordinary bag, as usually constructed, consists of a single piece, folded upon itself lengthwise, and the edges riveted or sewed together, or of two side pieces, secured in the same manner at the sides and one end. At the open end or mouth there is a row of metallic loops, secured to the inside, (which, when the bag is being filled, are in the way,) and which, upon closing the bag, pass through a series of openings on the opposite side of the bag. After the bag has been a short time in use, these metallic loops become loose, and are with difficulty passed through their respective openings, causing vexatious delays.

To secure the contents of the bag, the postmaster has to pass a strap, which is secured permanently at one end of the row of loops, through the entire series, and then around to and over a staple upon the opposite side of the series, where it is secured by the usual padlock. Bags thus constructed necessitate the use of a frame, purposely constructed, to hold them open in the act of filling, or the attendance of a second person, to support the mouth of the bag while the mail-matter is being deposited therein. All these movements are matters of considerable time—often valuable time. In contradistinction, I now pass to the

Operation of my Improved Bag.

The bag and jaws being as shown in fig. 2, the left hand grasps the handle K, (or it may be caught upon a suitable hook, for that purpose provided, upon the edge of the mailing-table or bin, thus allowing the post-master or clerk unrestricted liberty of both hands.) The mail-matter is thrown readily into the mouth of the bag, which the jaws keep distended. When full, the jaws A B are brought together, by which action the projections f f pass through the openings g g, in the shield E. The bar D is then moved endwise by the button G, by which motion the tongues e e are passed through the openings in f f, while at the same time the loop d is passed through both the flanges, a and b, thus firmly securing both jaws together, and, of course, the matter in the bag, the security being completed by passing the bar of a common post-office padlock through the protruding loop d, and locking the same.

The use of the bolster-strip H, in the construction of my improved bag, while adding but a trifle to the extra cost of manufacture, adds greatly to the capacity of the bag, as will be readily admitted upon the most casual observation, while the manner in which the labor of mailing matter is expedited will be at once manifested.

Having thus described the construction and operation of my improved mail-bag, what I claim, and desire to secure to myself by Letters Patent, is—

The construction of the mouth-frame A B, with its several parts, as herein constructed and set forth.

D. FRANK DODGE.
